(57) **CLAIM**

The ornamental design for a pump for liquids, as shown and described.

DESCRIPTION

The patent or application file contains at least one drawing executed in color. Copies of this patent or patent application publication with color drawing(s) will be provided by the Office upon request and payment of the necessary fee.

The design relates to a pump that may in particular be a diaphragm liquid pump. The broken lines represent portions of the PUMP in which the design is embodied that form no part of the claimed design. The ghosted regions within the bounds of the broken lines depict portions of the pump for liquids that form no part of the claimed design.
